UNITED STATES PATENT OFFICE.

VERNON G. KAY, OF CLEVELAND, OHIO, ASSIGNEE TO THE SCOTT-ULLMAN COMPANY, OF CLEVELAND, OHIO, A CORPORATION OF OHIO.

LIGHTING FIXTURE.

Application filed January 20, 1926. Serial No. 82,435.

This improvement, relating as indicated to illuminating devices, has more particular reference to a construction which may be made up readily and in different degrees 5 of complexity in accordance with the requirements in any given instance. Customarily a fixture-manufacturer in order to meet the wide scope of requirements of the trade is compelled to put out a wide range 10 of equipment, which in the tubular and cast type as now employed involve very extensive outlays and stocks. A type of construction which is of unit character and simple to make and easy to assemble in different arrangements is accordingly highly to 15 be desired.

To the accomplishment of the foregoing and related ends, the invention, then, consists of the features hereinafter fully described. 20 and pointed out in the claims, the annexed drawing illustrating but a few details of the various forms, however, in which the principle of the invention may be employed.

In said annexed drawing:

25 Fig. 1 is a view partly in section and partly in elevation of one-half of a construction embodying my invention, the symmetrical remainder being omitted in order to allow of a large scale showing; Figs. 2 and 3 are plane and edge views respectively 30 of the make-up unit in course of manufacture; Fig. 4 is a detail showing the manner of assembling the units; and Fig. 5 is a similar view showing the manner of concealing 35 the points of assembly.

Referring more particularly to the drawing, the reference character A designates a make-up unit having an attaching arm 1 and a carrier arm 2. The attaching arm is bowed out more or less in shape as desired, and extending integrally therefrom is the carrier arm, this being formed by shearing from the margins, or preferably within the contour of the carrier arm as indicated in 40 Fig. 2, and then being bent out angularly to the desired extent. The first mentioned operation is performed in a suitable shear or punch press, a plate or sheet metal blank being the raw material, and the second 45 operation may be accomplished in the same press or otherwise as convenient. An ornamental stamping is also provided as at 3 and holes 4, 5, 6 and 7 are punched near the ends and intermediately for a purpose to be 50 referred to more in detail hereinafter. 55 Semicircular holes 8 are also punched and a strap like bridge 9 is sheared in connection therewith. By bending the respective arms to the extent desired, various ornamental shapes may be produced, the general 60 type preferably being somewhat along the lines shown in Fig. 1. As here shown, the attaching arm 1 is bowed outwardly so as to allow the upper end to extend almost vertically while the lower end extends almost 65 horizontally, and the carrier arm 2 is bent out substantially horizontally with one or more ornamental curvatures. The make-up unit with its arms shaped into final form, with the bridge 9 bowed or offset from the 70 plane of the arm is secured to any suitable supporting means and may be used as such, a lamp socket 10 being secured in the loop 9 of the carrier arm. By assembling two or more of these units together, fixtures of 75 greater complexity and ornamental effect may be had, conveniently a central hollow stem 14 extending from a support 18 and having thereon an annular member 11 to which the make-up units are secured by their 80 lower ends by screws or the like 12. A coupling 13 having lateral openings is carried by the central stem and to ornamenteally conceal 85 the joints of the assembled structure, a cup-like member 15 of ornamental design is held in place on the coupling by a cap 16 from which there may be an ornamental pendant 17. The upper ends of the attaching arms 1 may be secured to the support 18 by small 90 bolts or the like 19 passed through the holes 4. The wires leading to the lamps are passed through the hollow central stem and out through the lateral openings in the coupling, thence through the opening 6 in the arm and along the back of the arm to 95 the opening 8 through which they lead to the lamp socket 10. To hold the wires in place, pins 21 may be inserted through the holes 5 and be sufficiently bent over to retain the 100 wires, and advantageously the same pin may be used to suspend an ornamental pendant of glass or other desired material 22. By using different numbers of the make-up units, a variety of finished fixtures is possible 105 and in each case the general plan of wiring is the same as indicated. It will thus be seen that the construction as a whole allows of quite a range of effects and withal is

simple and of relatively low cost in manufacture.

Other modes of applying the principle of my invention may be employed instead of those explained, change being made as regards the means herein disclosed, provided the means stated by any of the following claims or the equivalent of such stated means be employed.

10 I therefore particularly point out and distinctively claim as my invention:—

1. In a device of the character described, a make-up unit having an attaching arm and a carrier arm sheared and bent out therefrom at an angle, and an integral loop near the free end of said carrier arm, said loop being offset from the plane of the carrier arm to leave an opening.

2. In a device of the character described, a make-up unit having an attaching arm and a carrier arm sheared within the contour thereof and bent out at an angle, said carrier arm having near its free end an integral loop offset from the plane of the arm to leave an opening, and means on said attaching arm

for suspending a pendant and for holding an electric conductor.

3. In a device of the character described, a plurality of units having attaching arms and carrier arms sheared and angularly bent out therefrom, each said carrier arm having near its free end an integral loop offset from the plane of the arm to leave an opening, a central stem, and support members joined by said stem, said attaching arms being secured to the support members.

4. In a device of the character described, a plurality of units having attaching arms and carrier arms sheared and angularly bent out therefrom, each said carrier arm having near its free end an integral loop offset from the plane of the arm to leave an opening, and each attaching arm having means for suspending a pendant and holding an electric conductor, a central stem, and support members joined by said stem, said attaching arm being secured to the support members.

Signed by me this 16th day of January, 1926.

VERNON G. KAY.
